MIXING CIRCUIT ARRANGEMENT

Adelbert van Weel, Eindhoven, Netherlands, assignor to Hartford National Bank and Trust Company, Hartford, Conn., as trustee

Application July 20, 1946, Serial No. 685,204
In the Netherlands November 12, 1943

Section 1, Public Law 690, August 8, 1946
Patent expires November 12, 1963

8 Claims. (Cl. 250—20)

1

This invention relates to a mixing circuit-arrangement which is particularly suitable for use on short waves and in which the incoming oscillations are supplied in push-pull and the local oscillations produced by an oscillator are supplied in single phase to the input electrodes of two mixing systems. When transmitting ultrahigh frequencies, this method offers the advantage that a smaller input damping and a better signal-to-noise ratio are obtained.

It has previously been proposed that in such a circuit-arrangement the cathodes of the mixing systems and of one or more discharge systems used in the local oscillator, should be mutually connected. In this case the various discharge systems may be housed in a single discharge tube. It is then sometimes not possible to connect the junction of the cathodes directly to a point of constant potential, such as ground, because the said junction is connected to the corresponding connecting pin of the discharge tube through a comparatively long connecting lead. In the case of short waves, this connecting lead constitutes a considerable inductance which is included in the cathode lead of the local oscillator causing a considerable negative feed-back, due to which the oscillator circuit can be set into oscillation only with great difficulty, if at all.

In order to avoid this difficulty, it is necessary to include a definite impedance, generally one having a high value, between the connecting pin and ground. However, as will appear hereinafter, the employment of such a high impedance entails the drawback that the voltage having the frequency of the local oscillations which is set up between the input electrodes of the mixing systems cannot be raised to a high value without any further expedients. The invention provides a means whereby this difficulty is prevented and whereby the local oscillations produced can be supplied efficaciously to the mixing systems.

According to the invention, between the junction of the cathodes and a point having a constant potential there is included a first impedance which forms part of a single-phase circuit constituted by the parallel-connected impedances of the two halves of the push-pull circuit, the parallel-connected input impedances of the mixing systems, and the impedances common to the input circuits of these systems. The single phase circuit is tuned in such a manner that a maximum voltage having the frequency of the local oscillations is set up between the mixer electrodes.

That branch of the single-phase circuit which extends from the said junction via the mixing

2

systems to the point of constant potential preferably includes a second impedance. The values of the first and second impedances are adjusted in such a manner that a maximum voltage having the frequency of the local oscillations is set up between the mixer electrodes. It is also possible to include a network between the junction of the cathodes and/or the point of constant potential on the one hand and the input electrodes not directly connected to each other and/or the points of connection of the aerial on the other hand, and to adjust this network and the said first impedance in such a manner that a maximum voltage having the frequency of the local oscillations is set up between the mixer electrodes.

As a rule, the push-pull circuit constituted by the impedances included between the input electrodes not directly connected to each other is tuned to the frequency of the incoming oscillations.

The oscillations received by the antenna may be transmitted to the push-pull circuit either directly or via an amplifier; the points of connection of the antenna and of the amplifier are preferably chosen such that a voltage node for the local oscillation frequency occurs at these points. This prevents the antenna from re-radiating the local oscillations and the amplifier from acting upon the tuning of the single-phase circuit.

In order that the invention may be clearly understood and readily carried into effect, it will now be explained more fully with reference to the accompanying drawing.

Figure 1 shows a circuit embodying the invention as applied to a mixing circuit;

Figure 2 shows an arrangement corresponding to the general scheme of Figure 1 and in addition showing the added impedances Z_3' , Z_3'' , and Z_4 , by which it is possible to adjust the position of the node of voltage of the intermediate frequency to coincide with the point of connection of the antenna, D' , D'' , thereby eliminating reradiation;

Figure 3 shows a further embodiment of the invention wherein the impedances Z_3' , Z_3'' , and Z_4 are replaced by a single impedance Z_3 ; and

Figure 4 shows an embodiment of the invention wherein a resonant circuit is coupled between the antenna connections and ground.

Figure 1 shows a mixing circuit arrangement which forms part of a superheterodyne receiver for short waves and in which the invention is applied. The oscillations received by a dipolar

antenna D', D'' are supplied to two conductors L_{1'}, L_{1''}, which jointly constitute a Lecher system which may be tuned to the frequency of the incoming oscillations by means of a short-circuiting bridge K. The Lecher system L_{1'}, L_{1''}, is connected to the anodes of two diode mixing tubes T_{1'}, T_{1''}. The antenna D', D'' is so connected to the Lecher system L_{1'}, L_{1''}, as to obtain the correct matching of the antenna to the mixing tubes T_{1'}, T_{1''}. The input impedance of the mixing tubes are constituted by the capacities C_{1'}, C_{1''}.

The local oscillations are produced by a local oscillator O. This oscillator is constituted by a triode T₂ and an oscillatory circuit which is constituted by a capacity C₂ and an inductance L₂ and which is included between the control grid and the anode of the triode T₂.

The cathodes of the two mixing diodes T_{1'}, T_{1''}, and the cathode of the oscillatory triode T₂ are connected to one another at point P. The junction P is connected to earth via a variable impedance Z₁; the short-circuiting bridge K is connected to earth through a variable impedance Z₂.

A resonant circuit tuned to the intermediate frequency and constituted by a coil L₄ and a condenser C₄ is connected in push-pull to the anodes of the two diodes via two high-frequency chokes L_{3'}, L_{3''}. The chokes are provided for the purpose of preventing transmission of the incoming high-frequency oscillations to the parts of the receiver following the mixing stage. A leakage resistance R₁ is included between the middle of the coil L₄ and ground. The intermediate-frequency circuit L₄—C₄ is separated from the push-pull circuit by two blocking condensers C_{3'}, C_{3''}. The coil L₄ is in addition coupled inductively to a second intermediate-frequency circuit L₅, C₅ from which the output voltage of the circuit-arrangement is taken. For clearness sake the direct-current sources are omitted in the figures.

In order to set the local oscillator into oscillation a sufficiently high impedance must exist between point P and ground. The value of this impedance is determined both by the value of the variable impedance Z₁ and the value of the impedance between point P via the diodes T_{1'}, T_{1''}, to ground. As the value of this impedance is made higher, the local oscillator oscillates more satisfactorily and a higher voltage of the frequency of the local oscillations is set up across the impedance Z₁.

According to the invention, this voltage is supplied to the mixing stage, more particularly to the two diodes T_{1'}, T_{1''}, by arranging in parallel with the impedance Z₁, the push-pull connected diodes, the Lecher system L_{1'}, L_{1''}, the short circuiting bridge K, and the variable impedance Z₂. If the impedance Z₁ could be regarded as a source for the local oscillations whose internal resistance is negligible, the voltage of the local oscillations set up across the diodes T_{1'}, T_{1''} would be maximized if the described series-connection arranged in parallel with the impedance Z₁ were tuned to the frequency of the local oscillations. This is so because if this series-connection, which is constituted by the parallel-connected impedances of the two halves of the push-pull circuit (L_{1'}, L_{1''}; C_{3'}, C_{3''}), the parallel-connected input impedances of the two discharge systems (C_{1'}, C_{1''}) and the impedance Z₂, is in resonance for the frequency of the local oscillations, a maximum voltage of the frequency of the local oscillations is set up across the diodes. In this case,

however, a series-connection is provided between point P and earth, which connection has a very small impedance for this frequency, due to which the local oscillator stops oscillating. To prevent this, and to obtain nevertheless as high a voltage of the frequency of the local oscillations as possible across the diodes, the whole single phase circuit, in the present case the said series-connection together with the variable impedance Z₁, is tuned in such a manner that a maximum voltage of the frequency of the local oscillations is set up between the input electrodes of the diodes.

In the circuit-arrangement shown in Figure 1 this is achieved by including an impedance Z₂ in the right branch of the single-phase circuit, i. e. the said series-connection between point P and earth, and by adjusting the impedances Z₁ and Z₂ in such a manner that a voltage maximum is set up across the diodes.

If the single-phase circuit is adjusted to a voltage maximum by means of the impedances Z₁ and Z₂, there is in general between point P and earth an impedance which may be constituted by an inductance or a capacity, since the circuit is, as a rule, not tuned to the frequency of the local oscillations. However, in certain cases it may be necessary to tune the single-phase circuit to this frequency in order to obtain a maximum voltage across the diodes. In this case there is a tuned circuit between point P and earth, which behaves like a real resistance for the frequency of the oscillator.

As a rule, it is still desirable to arrange the antenna in a voltage minimum for the frequency of the local oscillations without disturbing the optimum adaptation of the antenna to the mixing tubes. Figure 2 shows a circuit-arrangement by which this can be achieved.

In the circuit shown in Figure 2 the discharge systems T_{1'}, T_{1''} and T₂ are housed in one discharge tube T₃. Furthermore, between the two halves of the push-pull circuit, viz. between the two anodes of the diodes and ground there is included a network constituted by the series-connection of two impedances Z_{3'}, Z_{3''}, whose junction is grounded through an impedance Z₄. In a practical form of construction, the impedances Z_{3'}, Z_{3''} may be inductance coils and the impedance Z₄ a condenser.

The push-pull circuit is tuned to the frequency of the incoming oscillations by means of the short-circuiting bridge K. The inductance of the coils Z_{3'}, Z_{3''} is given so high a value that their presence has little or no influence on the tuning of the push-pull circuit. The antenna D', D'' is connected to the Lecher system L_{1'}, L_{1''} so as to obtain the optimum adaptation, i. e. maximum signal-to-noise ratio or maximum amplification, of the antenna to the mixing systems. Now the impedance Z₂ is adjusted in such a manner that the points of connection of the antenna exhibit a voltage minimum for the frequency of the local oscillations, i. e. that the parallel-connected right halves of the Lecher leads L_{1'}, L_{1''}, taken from the points of connection of the antenna, jointly with the impedance Z₂ are tuned to the frequency of the local oscillations. Finally, the condenser Z₄ is adjusted in such a manner that the maximum voltage of the frequency of the local oscillations is set up across the diodes.

Instead of providing the described network, it frequently suffices to include a variable impedance between the anodes of the diodes. In this case the maximum voltage across the diodes is

obtained by adjusting the variable impedances Z_1 and Z_2 . By adjustment of the impedance included between the anodes and by adjustment of the short-circuiting bridge K , it may be ensured that the antenna is connected in a voltage minimum for the local oscillations and is at the same time so adapted as to be optimum to the mixing systems, while moreover the push-pull circuit is tuned to the frequency of the incoming oscillations. A circuit arrangement of this type is illustrated in Fig. 3, where element Z_3 represents the variable impedance included between the mixer anodes.

For connecting the antenna in a voltage minimum for the frequency of the local oscillations it is alternatively possible to include a resonant circuit tuned to this frequency between the points of connection of the antenna and earth. Such a circuit may be constituted, for example, by two series-connected coils or condensers which are included between the said points of connection and whose junction is earthed through a condenser or a coil. Such a circuit is illustrated in Fig. 4, where coils L_6' and L_6'' are connected in series between the junction points of antenna D' , D'' and Lecher-line L_1' , L_1'' and a condenser C_6 is connected between the junction of coils L_6' and L_6'' and ground.

What I claim is:

1. A circuit arrangement for mixing a first wave and a second wave to produce an intermediate frequency wave, comprising a pair of mixing elements each having input and cathode electrodes, a Lecher-system having an open end thereof coupled to the input electrodes of said mixing elements in push-pull relationship and having a closed end, means to generate said first wave including an electron discharge system having a cathode, means to couple together the cathodes of said mixing elements and the cathode of said discharge system to define a junction, means to apply said second wave to said Lecher-system, a first impedance network coupled between said junction and a point of constant potential, a second impedance network coupled between the closed end of said Lecher-system and said point of constant potential, the relative impedance values of said first and second impedance networks being adjustable to maximize the voltage produced across said mixing elements by said first wave, a network having an electrical center and coupled between the input electrodes of said mixing elements, and an impedance element connected between said electrical center and said point of constant potential.

2. A circuit arrangement for mixing a first wave and a second wave to produce an intermediate frequency wave, comprising a pair of mixing elements each having anode and cathode electrodes, a Lecher-system having an open end thereof coupled to the anode electrodes of said mixing elements in push-pull relationship and having a closed end, means to generate said first wave including an electron discharge system having a cathode, means to couple together the cathodes of said mixing elements and the cathode of said discharge system to define a junction, means to apply said second wave to said Lecher-system, a first impedance network coupled between said junction and ground, a second impedance network coupled between the closed end of said Lecher-system and ground, the relative impedance values of said first and second impedance networks being adjustable to maximize the voltage produced across said mixing elements by

said first wave, a network tuned to the frequency of said intermediate frequency wave and having an electrical center and coupled between the anode electrodes of said mixing elements, and an impedance element connected between said electrical center and ground.

3. A circuit arrangement for mixing a first wave and a second wave to produce an intermediate frequency wave, comprising a pair of mixing elements each having anode and cathode electrodes, a Lecher-system having an open end thereof coupled to the anode electrodes of said mixing elements in push-pull relationship and having a closed end, means to generate said first wave including an electron discharge system having a cathode, means to couple together the cathodes of said mixing elements and the cathode of said discharge system to define a junction, means to apply said second wave to said Lecher-system at a point of voltage node of said first wave, a first impedance network coupled between said junction and a point of constant potential, a second impedance network coupled between the closed end of said Lecher-system and said point of constant potential, the relative impedance values of said first and second impedance networks being adjustable to maximize the voltage produced across said mixing elements by said first wave, a network having an electrical center and coupled between the anode electrodes of said mixing elements, and an impedance element connected between said electrical center and said point of constant potential.

4. A circuit arrangement for mixing a first wave and a second wave to produce an intermediate frequency wave, comprising a pair of mixing elements each having input and cathode electrodes, a Lecher-system having an open end thereof coupled to the input electrodes of said mixing elements in push-pull relationship and having a closed end, means to generate said first wave including an electron discharge system having a cathode, said mixing elements and said discharge system being included in an electron discharge tube, means to couple together the cathodes of said mixing elements and the cathode of said discharge system to define a junction, means to apply said second wave to said Lecher-system, a first impedance network coupled between said junction and a point of constant potential, a second impedance network coupled between the closed end of said Lecher-system and said point of constant potential, the relative impedance values of said first and second impedance networks being adjustable to maximize the voltage produced across said mixing elements by said first wave, a network having an electrical center and coupled between the input electrodes of said mixing elements, and an impedance element connected between said electrical center and said point of constant potential.

5. A circuit arrangement for mixing a first wave and a second wave to produce an intermediate frequency wave, comprising a pair of mixing elements each having anode and cathode electrodes, a Lecher-system having an open end thereof coupled to the anode electrodes of said mixing elements in push-pull relationship and having a closed end, means to generate said first wave including an electron discharge system having cathode, control grid and anode electrodes and an oscillatory circuit tuned to the frequency of said first wave coupled between the control grid and anode electrodes of said discharge system, means to couple together the cathodes of

said mixing elements and the cathode of said discharge system to define a junction, means to apply said second wave to said Lecher-system, a first impedance network coupled between said junction and a point of constant potential, a second impedance network coupled between the closed end of said Lecher-system and said point of constant potential, the relative impedance values of said first and second impedance networks being adjustable to maximize the voltage produced across said mixing elements by said first wave, a network having an electrical center and coupled between the anode electrodes of said mixing elements, and an impedance element connected between said electrical center and said point of constant potential.

6. A circuit arrangement for mixing a first wave and a second wave to produce an intermediate frequency wave, comprising a pair of mixing elements each having anode and cathode electrodes, a Lecher-system having an open end thereof coupled to the anode electrodes of said mixing elements in push-pull relationship and having a closed end, means to generate said first wave including an electron discharge system having a cathode, means to couple together the cathodes of said mixing elements and the cathode of said discharge system to define a junction, means to apply said second wave to said Lecher-system, a first impedance network coupled between said junction and a point of constant potential, a second impedance network coupled between the closed end of said Lecher-system and said point of constant potential, the relative impedance values of said first and second impedance networks being adjustable to maximize the voltage produced across said mixing elements by said first wave, a network having an electrical center and coupled between the anode electrodes of said mixing elements, a first impedance element connected between the electrical center and said point of constant potential, and a third impedance network including second and third impedance elements coupled in series between the anodes of said mixing elements and a fourth impedance element coupled between the junction of said second and third impedance elements and said point of constant potential.

7. A circuit arrangement for mixing a first wave and a second wave to produce an intermediate frequency wave, comprising a pair of mixing elements each having anode and cathode electrodes, a Lecher-system having an open end thereof coupled to the anode electrodes of said mixing elements in push-pull relationship and having a closed end, means to generate said first wave including an electron discharge system having a cathode, means to couple together the cathodes of said mixing elements and the cathode of said discharge system to define a junction, means to apply said second wave to said Lecher-system, a first impedance network coupled between said junction and a point of constant potential, a second impedance network coupled between the closed end of said Lecher-system

and said point of constant potential, the relative impedance values of said first and second impedance networks being adjustable to maximize the voltage produced across said mixing elements by said first wave, a network having an electrical center and coupled between the anode electrodes of said mixing elements, an impedance element connected between said electrical center and said point of constant potential, and an adjustable impedance element coupled between the anodes of said mixing elements.

8. A circuit arrangement for mixing a first wave and a second wave to produce an intermediate frequency wave, comprising a pair of mixing elements each having anode and cathode electrodes, a Lecher-system having an open end thereof coupled to the anode electrodes of said mixing elements in push-pull relationship and having a closed end, means to generate said first wave including an electron discharge system having a cathode, means to couple together the cathodes of said mixing elements and the cathode of said discharge system to define a junction, means to apply said second wave to said Lecher-system at points of voltage node of said first wave, a first impedance network coupled between said junction and a point of constant potential, a second impedance network coupled between the closed end of said Lecher-system and said point of constant potential, the relative impedance values of said first and second impedance networks being adjustable to maximize the voltage produced across said mixing elements by said first wave, a network having an electrical center and coupled between the anode electrodes of said mixing elements, a first impedance element connected between said electrical center and said point of constant potential, second and third impedance elements coupled in series between said points of voltage node on said Lecher-system, and a fourth impedance element coupled between the junction of said second and third impedance elements and said point of constant potential.
